CHARLES M. SAEGER, OF ALLENTOWN, PENNSYLVANIA.

ELECTRIC SIGNAL.

1,142,912.

Specification of Letters Patent. Patented June 15, 1915.

Application filed February 15, 1915. Serial No. 8,251.

To all whom it may concern:

Be it known that I, CHARLES M. SAEGER, a citizen of the United States, residing at Allentown, in the county of Lehigh and State of Pennsylvania, have invented certain new and useful Improvements in Electric Signals, of which the following is a specification.

This invention consists of a combination and arrangement of electric devices or apparatus operating in conjunction with an ordinary automatic railway block signal system, yet virtually independent of the same, and designed to detect and report any 10 train which may violate the general rule against passing block signals when in "danger" or "stop" position. The device will send a record to headquarters, usually the despatcher's office, the instant a train 15 passes a block signal when its semaphore or target is in "stop" or "danger" position, and the number of this signal (all signals being properly numbered) will be indicated, as well as the exact time of passing the 20 same. As all railroads maintain a train sheet at the despatcher's office, containing a complete record of all trains, the offending train can readily be identified by consulting such train sheet, and proper disciplinary 25 measures taken.

The various systems of automatic block signals used on railroads are, as a rule, very satisfactory, and if the rules governing the use thereof were strictly observed by the locomotive engineers, these systems would be practically infallible. However, such is not the case, as the numerous and frequent train wrecks occurring in all parts of the country, occasioned by engineers running past stop 35 signals, show that the block signal system cannot control this human element, namely a disobedient or careless engineer. This is the weak spot or defect of automatic block signals, which is covered or controlled by 40 the present invention, the same reporting all infringement of the rules. An engineer knowing that the apparatus is in use on his road, and cognizant of the fact that his job is at stake on the first infringement of the 45 rule against passing signals when in stop position, will be apt to be intensely vigilant, and thus infringement of the rule will be of extremely rare occurrence.

In order that the invention may be better understood, reference is had to the accompanying drawing, in which—

Figure 1 is a diagrammatic view of the apparatus, and Fig. 2 is a similar view showing certain parts in another position.

Referring specifically to the drawing it will be seen that the invention consists of a metallic main electrical circuit from each block signal on any railroad system operating such signals, and extending to some central station, usually the despatcher's office. This circuit has at the office some standard annunciator board with drops showing numbers of all the block signals on a division, and also a stop clock to record the time of any drop in action; or a standard recording instrument, with paper on which the number of signal and time will be graphically recorded. Various other recording devices may be employed, the particular type of such apparatus not being material.

The drawings show diagrammatically a suitable recording instrument or apparatus K from which the conductors 1 and 2 of the main circuit extend. A block signal semaphore arm is shown at D to which the conductor 1 is connected in such a manner that the circuit is closed only when said arm is in a horizontal or "stop" position. When the semaphore arm is in vertical ("proceed") or at an angle ("caution") position, the circuit is always open or broken. Any suitable switch controlled by the semaphore arm as described may be employed. From this switch the conductor 1 is continued and connected to one pole of a battery F or other source of electric energy, and from the other pole of the battery the conductor extends and is connected to an insulated rail section A of the track. The conductor 2 extends from the recording instrument K and connects with a standard relay E at the contact H, and thence continues from the armature lever J of the relay to a rail section A¹ of the track opposite the section A. Next to the rail sections A, A¹ and insulated therefrom, are rail sections B and B¹ which are also insulated from the main block rails C and C¹. The rails A and A¹ and B, B¹ are located at the entrance of the block, the rails A and A¹

being the first ones, so that a train entering the block first passes over said rails, and then over the rails B and B¹ before passing to the main block rails C and C¹. The 5 rails A and A¹ are also insulated from the main block rails of the preceding block.

At G is shown a local battery or other source of electric energy. From one pole of this battery a conductor 3 extends and is 10 connected to the rail section B¹. A conductor 4 from the other pole of the battery is connected to the windings of the relay E and then extends and is connected to the rail section B.

15 The operation of the device is as follows: When a train is in the block on the rails C and C¹, the semaphore arm D is thrown to horizontal position, calling for a stop of any following train. The main circuit controlling the recording instrument K is now 20 closed at D, and the relay lever J touches the contact H the armature lever J touches the contact H closing the main circuit at this point. The circuit is, however, still open between the 25 rails A and A¹. Now, if a train enters the rails A and A¹ in an attempt to pass the block signal, the main circuit is closed by the current passing from rail A to rail A¹ through the engine or car axles. The main 30 circuit being now closed at all points, a record will be made by the instrument K in the despatcher's office. The exact time of record is also made, and thus the infringement of the rule is recorded and reported, and by 35 consulting the train sheet, the number of the train, engine and name of engineer can be determined. When the rails C, C¹ of the block are unoccupied, the semaphore arm D will be vertical, opening the main circuit at 40 this point, and then any train may pass over rails A, A¹ and B, B¹ without a report being made at the despatcher's office.

45 After a train has passed the rails A, A¹ and B, B¹, and entered onto rails C, C¹, the semaphore arm D will fall to horizontal or "stop" position, and without the insulation of rails B, B¹ and the use of the relay E connected to these rails, a false report would be sent, as one or more of the cars of the 50 train may still be on the rails A, A¹. The function, therefore, of rails B, B¹ and relay E, is to open or break the main circuit and prevent reporting as long as any cars are on the rails B, B¹. The current from source G 55 passing through the car axles when on rails B, B¹ completes the auxiliary or relay circuit, drawing up the armature J of the relay E, thus breaking the main circuit at H, as shown in Fig. 2.

60 It will be readily seen that the invention is absolutely independent of the main block signal system, and the operation of the latter is not interfered with. A simple attachment to the semaphore shaft to open or close a 65 switch is all that is required, and there is no

electrical connection with the block signal apparatus. The invention may be operated with either a closed or open circuit as may be desired.

70 I claim:

1. The combination with a railway block signal system; of a track section at the entrance of the block having its rails insulated from the main block rails, an electric circuit having conductors connected respectively to the rails of said track section, a recording apparatus operatively connected to the circuit, and a switch in said circuit governed by the condition of the signal device of the block, the circuit being closed at said switch 80 when the signal device indicates "stop."

2. The combination with a railway block signal system; of a track section at the entrance of the block having its rails insulated from the main block rails, an electric circuit 85 having conductors connected respectively to the rails of said track section, a recording apparatus operatively connected to the circuit, and a switch in said circuit governed by the condition of the signal device of the 90 block, the circuit being closed at said switch when the signal device indicates "stop," and means for opening the circuit after a train passes onto the main block rails with a portion of said train remaining on the rails of 95 the aforesaid track section.

3. The combination with a railway block signal system; of separate track sections at the entrance of the block having their rails insulated from each other and from 100 the main block rails, a main electric circuit having conductors connected respectively to the rails of one of said track sections, a recording apparatus operatively connected to the main circuit, a switch in 105 said circuit governed by the condition of the signal device of the block, the switch being closed when the signal device indicates "stop," and an electrically-operated circuit making and breaking device for the 110 main circuit, said circuit including a current source and conductors connected to the rails of the other track section, said rails being in advance of the rails of the first mentioned track section.

115 4. The combination with a railway block signal system; of separate track sections at the entrance of the block having their rails insulated from each other and from the main block rails, a main electric circuit having conductors connected respectively to the rails of one of said track sections, a recording apparatus operatively connected to the main circuit, a switch in 120 said circuit governed by the condition of the signal device of the block, the switch being closed when the signal device indicates "stop," and an auxiliary electric circuit including a current source, a relay and conductors connected to the rails of the other track section, said rails 125 130

being in advance of the rails of the first mentioned track section, said relay controlling the main circuit.

5. The combination with a railway block signal system; of an electric circuit, a recording apparatus operatively connected to the circuit, a switch in said circuit governed by the condition of the signal device of the block, the switch being closed when 10 the signal device indicates "stop," and train-controlled circuit closing means in said circuit at the entrance of the block.
6. The combination with a railway block signal system; of an electric circuit, a recording apparatus operatively connected to the circuit, a switch in said circuit governed by the condition of the signal device of the block, the switch being closed when 15 the signal device indicates "stop," train-controlled circuit closing means in said circuit at the entrance of the block, and means for opening the circuit after a train passes into the block with a portion of said train remaining outside the block.
- 20 7. The combination with a railway block signal system; of a main electric circuit, a recording apparatus operatively connected to said circuit, a switch for the main circuit governed by the condition of the signal device 25 of the block, the switch being closed when the signal device indicates "stop," an

electrically-operated auxiliary circuit making and breaking device for the main circuit, said auxiliary circuit including a current source, and separate train-controlled 35 circuit closing means for the main and the auxiliary circuits at the entrance of the block, the auxiliary circuit closing means being in advance of the main circuit closing means.

8. The combination with a railway block signal system; of a main electric circuit, a recording apparatus operatively connected to the main circuit, a switch in said circuit governed by the condition of the signal device 40 of the block, the switch being closed when the signal device indicates "stop," an auxiliary electric circuit including a current source, and a relay controlling the main circuit, and separate train-controlled 45 circuit closing means for the main and the auxiliary circuits at the entrance of the block, the auxiliary circuit closing means being in advance of the main circuit closing means.

In testimony whereof I affix my signature in presence of two witnesses.

CHARLES M. SAEGER.
